MECHANIC'S WORKBENCH

Alexander P. Fox, University City, and August D. Reisert, St. Louis, Mo., assignors to Lincoln Engineering Company, St. Louis, Mo., a corporation of Missouri

Application December 18, 1948, Serial No. 150,234

Term of patent 7 years

(Cl. D33—14)

To all whom it may concern:

Be it known that we, Alexander P. Fox and August D. Reisert, citizens of the United States and residents of University City, St. Louis County, Missouri, and St. Louis, Missouri, respectively, have invented a new, original, and ornamental Design for a Mechanic's Workbench, of which the following is a specification, reference being had to the accompanying drawing, forming part thereof, in which

Fig. 1 is a trimetric view, showing my new design;

Fig. 2 is a plan view;

Fig. 3 is a front elevation;

Fig. 4 is a left-end view of Fig. 3;

Fig. 5 is a right-end view of Fig. 3; and

Fig. 6 is a rear elevation.

We claim:

The ornamental design for a mechanic's workbench, substantially as shown.

ALEXANDER P. FOX.
AUGUST D. REISERT.
